[57] CLAIM

The ornamental design for a coordinate measuring machine, as shown.

DESCRIPTION

FIG. 1 is a front perspective view of a coordinate measuring machine showing our new design;

FIG. 2 is a front elevational view thereof;

FIG. 3 is a left side elevational view thereof, the right side elevational view being a mirror image thereof;

FIG. 4 is a top plan view thereof;

FIG. 5 is a rear elevational view thereof.

FIG -1

FIG -2

FIG - 3

FIG -4
